COTTON PICKING SPINDLE AND SLAT ASSEMBLY

Arthur L. Hubbard, Madrid, Iowa, assignor to Deere Manufacturing Co., Dubuque, Iowa, a corporation of Iowa

Application April 5, 1955, Serial No. 499,436

13 Claims. (Cl. 56—44)

This invention relates to a picker bar for a mechanical cotton picker.

A typical cotton picker of the general character referred to, representative patented disclosures of which appear in U. S. patents to Paradise 2,660,852 and Swim 2,669,080, will include one or more picking drums, each of which comprises a plurality of upright picker bars or columns carried by the drum for orbital movement about an upright axis. Each column carries internally thereof a vertical driving shaft which is intergeared with a plurality of vertically spaced, substantially horizontally extending picker spindles. As the drum rotates, orbital movement is given to the columns by means of a cam having a track therein which is followed by cranks secured respectively to the upper ends of the picker bars. In this fashion, the picker bars are oscillated and the spindles rotate respectively about their own axes. Because of the relatively complicated nature of the construction, servicing of the picker bars is quite a problem. Normally this will involve the removal of a picker bar in its entirety, because wear in the spindle driving mechanisms and bearings will be substantially uniform and if replacement is required it is more practicable to replace the entire assembly than to replace individual spindles. Heretofore, the removal of each picker bar has been a somewhat difficult task, because the picker bar must be released not only from its supporting bearings but also from the guiding cam track. According to the present invention, this servicing problem is eliminated by the provision of an improved and novel picker bar construction comprising a column having an open front from which the spindle assemblies may be removed in a group, thereby obviating the necessity of removing the picker bar from its supporting bearings. A further feature of the invention resides in the block structure in which the individual spindles are mounted. In one form of the invention, the block structure is made up of a one-piece secondary support and in another form of the invention the block structure comprises a plurality of individual blocks arranged in stacked fashion. The spindles are normally carried in the block structure, in either form of the invention, so as to remain with the block structure, whereby upon removal of the block structure the spindles remain with the block structure and are separated from the driving connections with the upright driving shaft. This eliminates the threading and unthreading of the spindles in to the support as is typical of prior art designs. Therefore, engagement of the spindle-driven elements with the driving elements on the shaft is more readily adjusted and the proper drive connections can be made.

The foregoing and other important objects and desirable features inherent in and encompassed by the invention will become apparent as two preferred embodiments of the invention are disclosed in detail in the following specification and accompanying sheets of drawings, the several figures of which will be described immediately below.

Fig. 1 is a side view, partly in section and with parts

broken away, illustrating a representative picker bar as mounted in upper and lower drum supports and as including a controlling crank that follows the cam guide.

Fig. 2 is an enlarged view as seen along the line 2—2 of Fig. 1.

Fig. 3 is a perspective exploded view, on a reduced scale, illustrating the assembly and disassembly of the picker bar and block structure.

Fig. 4 is a section, on an enlarged scale, as seen along the line 4—4 of Fig. 3.

Fig. 5 is a view, drawn to the scale of Figs. 2 and 4, as seen along the line 5—5 of Fig. 1.

Fig. 6 is a view similar to Fig. 1 but showing a modified form of structure.

Fig. 7 is a view similar to Fig. 3 and illustrating the structure of Fig. 6.

Fig. 8 is an elevational view, with parts broken away and shown in section, of a further modification of the structure.

Fig. 9 is a sectional view on the line 9—9 of Fig. 8.

As is more fully illustrated in the above-noted Paradise and Swim patents, a cotton picker drum has upper and lower supporting portions in the form of a drum head and a bottom plate, a portion of the former being shown here at 10 and a portion of the latter being illustrated at 12. The head and plate 12 carry therebetween a plurality of picker bars, only one of which is shown here as comprising an elongated hollow support or column 14. This column has top and bottom ends 16 and 18, respectively, and is of channel or U-shaped section (best shown in Fig. 4), the bight portion of the U affording a closed upright rear wall 20 and the legs of the U respectively affording upright parallel side walls 22. The wrap-around nature of the construction is accomplished by the use of fairly heavy gauge plate stock formed as illustrated. The expressions "front," "rear," "top" and "bottom" are used here as well as in the claims as words of convenience and not of limitation.

The bight portion or rear wall 20 of the column is of arcuate section less than a full circle but greater than a semicircle, for purposes to presently appear, and the forward or generally radial extent of the side walls 22 is fairly substantial so as to give the column considerable fore-and-aft depth.

Each side wall 22 has a free upright front edge 24, a substantially horizontal top edge 26 and a substantially horizontal bottom edge 28.

Top and bottom trunnions 30 and 32 are secured respectively to the top and bottom ends of the column 14, the trunnions forming in effect coaxial extensions of the bight portion 20 of the column. Securing of the trunnions to the ends of the column is preferably accomplished by welding, as indicated at 34 and 36, respectively. The diameter of each trunnion is substantially on the order of the transverse dimension or twice the radius of the bight portion or rear wall 20 of the column. Therefore, the top and bottom edges of the side walls project forwardly or are exposed. A top closure member 38 projects forwardly from the front arcuate portion of the top trunnion 30 and is secured along the top edges 26 of the side walls 22, welding again being the preferred form of securing. The closure member is in the form of a plate having an arcuate rear portion 40 to accommodate the front arcuate portion of the trunnion 30 and may be additionally welded to the trunnion as suggested at 42. The plate or closure member has a free transverse front edge 44 preferably coterminous with the front edges 24 of the side walls 22.

A substantially similar closure member or plate 46 projects forwardly from the trunnion 32, being welded to the side wall bottom edges 28 and to the trunnion 32 in a manner similar to that described for the top plate or clo-

sure member. The lower member has a free front edge 48, coterminous with the edges 24 and 44. All of these edges combine or are cooperative to establish or define an upright, elongated rectangular opening or slot 50, which leads to the hollow interior of the column 14.

The bottom trunnion 32 is journaled on a vertical pintle 52 that rises from the bottom drum plate 12. The upper trunnion 30 provides a journal coaxial with the pintle 52, this journal being effected by receipt of the trunnion in an upright bore 54 in the drum head 10. The trunnion 30 projects upwardly past the drum head 10 and has an integral upper portion 56 to which is connected a not unconventional crank 58. The crank has a follower 60 which runs in a cam track 62 of a typical cam control plate 64, these details being shown and described only generally because of their conventional nature as disclosed in the above-noted Paradise patent. Because of the mounting just described, the column 14 is capable of angular movement about the upright axis established by the pintle 52 and journaling of the trunnion 30 at 54 in the drum head 10.

Retention of the crank 58 on the upper portion 56 of the trunnion 30 may be accomplished as by a set screw 66. A typical drum head, of which the present drum head 10 is representative, will include a removable cap 68, the split relative to the drum head proper being indicated by the dotted line 70 (Fig. 1). Hence, it will be seen that the column 14 as a whole may be removed from the drum by separating the trunnion 30 from the drum head 10, the crank 58 from the trunnion 30 and the column from the pintle 52. On the basis of experience with prior art structures, this manner of disassembly is by no means an easy one, since the relationship of the individual picker bars to the drum is fairly complicated and in the interests of efficient operation this relationship should be disturbed as little as possible. Moreover, disassembly in the manner just described would require separation of column-contained driving mechanism from drum-carried driving mechanism. The column-contained driving mechanism is shown here as including an upright driving shaft 72 which is housed in a shaft-receiving space 74 afforded by the arcuate shape of the bight portion or rear wall 20 of the column 14. The upper end of the shaft 72 projects upwardly beyond the top portion 56 of the trunnion 30 and has keyed thereto a pinion 76 which is in constant mesh with a drum-carried drive gear, a portion of which is shown at 78, the drive relationship to this extent being similar to that shown in the Paradise patent. An internal anti-friction bearing 80 journals the upper end of the shaft 72 in the upper portion 56 of the trunnion 30.

The shaft 72 has pinned thereto in axially spaced relation a plurality of driving elements in the form of bevel pinions 82 and additional journaling of the shaft is accomplished by additional bearings carried in the bight portion of the column and journaling the shaft 72 via the hubs of certain of the bevel pinions 82. One such additional bearing is shown at 84 as comprising a needle bearing journaling the hub 86 of the next to the uppermost bevel pinion 82. It will be understood that other bearings, like the bearing 84, can be used throughout the structure where desired. Because of the arcuate shape of the bight portion or rear wall 20 of the column 14, previously described as being less than a full circle but greater than a semicircle, adequate support for the bearing 84 is afforded.

The interior of the column 14 provides a lubricant reservoir to which lubricant is supplied through an open passage 88 in the trunnion 30, the purpose of the lubricant being to lubricate the bearings 80 and 84 as well as the bevel pinions 82 in their drive connections to driven elements or other bevel pinions 90 on the inner ends, respectively, of a plurality of picker spindles 92, these spindles being journaled respectively on substantially horizontal axes in block structure designated in its entirety by the numeral 94.

In this form of the invention, the block structure 94 comprises a plurality of separate blocks 96, each carrying a pair of spindles 92, and the assembly being one in which the blocks 96 are in stacked fashion, each block 96, except the lowermost block, resting on the block below it. Each block has an upper surface 98 and a lower or undersurface 100. When the blocks are assembled as shown in Fig. 1, the undersurfaces of the blocks rest respectively on the top surfaces 98 of the respective lower blocks, with the exception, of course, of the lowermost of the blocks. The vertical height of the stacked block structure 94 is such that the top plate 38 forms a closure with the top surface 98 of the uppermost block. The same is true as to the cooperation between the lower closure member or plate 46 and the undersurface 100 of the lowermost block 96. This relationship seals the column against the escape of lubricant.

Each spindle 92 is carried in its associated block by means of appropriate bearings 102, 102' carried in a block bore 104. Each block has a front face 106 exposed at the front of the column (forwardly ahead of the front edges 24 of the side walls 22) and further has a rear face 108 spaced ahead of the column rear wall 20 to afford the shaft-receiving space 74. The nature of the mounting of each spindle 92 in the spindle-receiving bore 104 is such that the spindle is normally constrained against axial separation from its block. Hence, upon removal of the individual blocks, the pair of spindles carried thereby will remain with the block. The separable drive connection 20 established between the associated bevel pinions 82 and 90 permits this separation. Likewise, installation of the block in a rearward direction will result in reengagement of the associated bevel pinions. The blocks, either individually or as a group, are of course receivable in the column via the front opening or slot 50. Conversely, the blocks are forwardly removable from the column via the same slot or opening.

Mounting of the blocks in the column is accomplished by releasable means, here comprising a plurality of releasable fasteners or elements such as bolts 110 having nuts 112. Each block 96 has a transverse bore 114 which registers with slots or apertures 116 in the side walls 22 of the column. A bolt 110 is passed through a pair of the slots 116 and the registering bore 114. Because of the fore-and-aft elongation of the slots 116, the concerned block 96 may be adjusted fore and aft to secure the proper drive connection or mesh between the bevel pinions 82 and 90, after which the nut 112 may be tightened. This is true of course as to all of the blocks 96. Thus, the spindle-mounting means afforded by the block structure 94, here comprising the several separate blocks 96, may be removed from the support comprised by the column 14 without disturbing the relationship between the column and the drum and further without disturbing the relationship between the drive gearing 76-78.

A feature of the separate block arrangement as shown in Figs. 1 through 5 is the cooperative relationship between the surfaces 98 and 100. The surfaces 100 slide respectively on the surfaces 98 and, these surfaces being flat, cocking of the blocks 96 is prevented. This enables the use of a single fastener for each block, thus simplifying and cutting the cost of the design.

In that form of the invention shown in Figs. 6 and 7, the column structure, trunnion mounting and internal driving mechanism are the same as that described above. However, here the block structure, designated at 94a, comprises a one-piece assembly in which the spindles 92 are mounted respectively in spindle-receiving bores 104a. The block structure 94a has a single top surface 98a and a single bottom surface 100a, these surfaces cooperating respectively with the top and bottom closure members 38 and 46 to establish the lubricant reservoir within the column. Front and rear faces 106a and 108a bear the 65 same relationship to the column 14 as do the correspond-

ing surfaces in Figs. 1 through 5. Apart from the one-piece nature of the block structure 94a, all other structural and functional attributes are the same as those in Figs. 1 through 5, it being noted that the bolts 110 and nuts 112 are used to support and retain the block structure 94a via bolt-receiving bores 114a in that block structure.

In that form of the invention shown in Figs. 8 and 9, a column 14b has an arcuate rear wall 20b and integral forwardly extending legs 22b. A comparison of Figs. 9 and 4 will show that the wall 20b is substantially semicircular before it joins the walls 22b. However, in this case, the semicircular extent of the wall 20b is inadequate to support the bearing 84 on the shaft 72. Additional support for the bearing is afforded by a modified form of block structure 108b, which has a rear arcuate portion 109 that engages the front arcuate portion of the bearing 84. Whether the block structure is built up in sections as shown in Fig. 1 or is a single unit as shown in Figs. 6 and 7 is of no importance at the moment other than to understand that either type of block structure would be satisfactory in this modification. Thus the bearing 84 is supported in part by the column wall 20b and in part by the rear end of the block 108b. An oil groove 111 in the rear portion of the block facilitates the flow of lubricant from top to bottom of the column structure.

Other than the details noted, the structure is the same as previously described, the modified form of block structure 108b carrying spindles 92 and being secured to the legs 22b by means of a bolt 110 and nut 112. The block 108b has a bore 114b to receive the bolt 110 and the legs 22b are slotted at 116b to accommodate misalignment and manufacturing errors. The column 14b is shown as having an open front 50b for receiving the block structure 98b.

One of the advantages of this modification is that the shape of the bight portion 20b need not be held to such close tolerances, since the block 98b contributes to the support of the bearing 84. Moreover, the mounting of the bearing in this form of the invention is somewhat more secure than those described. Of further importance is the indexing of the block structure by engagement between the arcuate portion 109 and the bearing 84, which indexing determines the proper mesh of the associated bevel gears 82 and 90. The block structure 108b is provided with an appropriate number of spindle-receiving bores 104b, by means of which the spindle bearings 102 are received to support the spindles 92, respectively.

The major features of the invention have been outlined above. Others have been covered in the foregoing specification. Still others will occur to those versed in the art, as will various modifications and alterations in the preferred form of the invention illustrated, all of which may be achieved without departing from the spirit and scope of the invention.

What is claimed is:

1. A picker bar, comprising: an elongated column of U-shaped section and having top and bottom open ends, the bight portion of the U affording an upright rear wall and the legs of the U respectively affording upright, forwardly projecting side walls, each side wall having an upright front edge and substantially horizontal top and bottom edges; top and bottom trunnions secured respectively to the top and bottom ends of the column as coaxial extensions of the bight portion thereof, leaving the top and bottom edges exposed forwardly of the respective trunnions; top and bottom closure members projecting forwardly from the respective trunnions and secured respectively along said top and bottom edges, said members respectively having free front edges cooperative with the side wall front edges to define an elongated front opening in the column; an upright drive shaft journaled in the column and contained substantially coaxially in the bight portion thereof, said shaft having thereon axially spaced apart driving elements; elongated upright block structure rearwardly receivable in and normally supported by the

column and forwardly removable from the column via the front opening for disassembly, said structure having a rear face proximate to but spaced forwardly from the drive shaft when received in the column and further having a front face exposed at the front of the column, said structure having therein a plurality of substantially horizontal spindle bores equal in number to and vertically spaced apart on the order of the driving elements on the shaft, each bore opening at opposite ends respectively

5 at the front and rear faces of the block structure; a plurality of picker spindles journaled in the block structure, one in each bore and normally constrained against axial separation from said structure, each spindle having a rear end including a driven element rearwardly engageable with and forwardly disengageable from a respective driving element; and releasable means securing the block structure to the column.

2. The invention defined in claim 1, in which: the block structure is made up of a plurality of separate blocks, each block containing fewer than the total number of spindles and the blocks being arranged in vertically stacked fashion.

3. The invention defined in claim 2, in which: each block has substantially flat upper and lower surfaces and each block except the lowermost block has its lower surface resting on the upper surface of the next lower block.

4. The invention defined in claim 3, in which: the releasable means securing the block structure to the column comprises a plurality of releasable elements, one for each block and enabling individual removal of a selected block.

5. The invention defined in claim 4, in which: each releasable element includes provision for fore-and-aft independent adjustment of the respective block relative to the column and the other blocks to vary the driving engagement between the associated driving and driven elements.

6. The invention defined in claim 1, in which: the releasable means includes provision for fore-and-aft adjustment of the block structure relative to the column to vary the driving engagement between the driving and driven elements.

7. The invention defined in claim 1, in which: the block structure has a plurality of fastener-receiving bores transverse to and interspaced with certain of the spindle bores; the side walls have apertures respectively in register with the fastener-receiving bores when the block structure is received in the column; and the releasable means includes a plurality of fasteners passed respectively through the registered apertures and bores.

8. A picker bar, comprising: an elongated column of U-shaped section and having top and bottom ends, the bight portion of the U affording an upright rear wall and the legs of the U respectively affording upright, forwardly projecting side walls, each side wall having an upright front edge and said front edges being spaced apart to afford an elongated upright front slot leading to the interior of the column; top and bottom trunnions secured respectively to the top and bottom ends of the column as coaxial extensions thereof; an upright drive shaft journaled in the column and contained substantially coaxially in the bight portion thereof, said shaft having thereon axially spaced apart driving elements; elongated upright

55 block structure rearwardly receivable in and normally supported by the column and forwardly removable from the column via the front slot for disassembly, said structure having a rear face proximate to but spaced forwardly from the drive shaft when received in the column and further having a front face exposed at the front of the column, said structure having therein a plurality of substantially horizontal spindle bores equal in number to and vertically spaced apart on the order of the driving elements on the shaft, each bore opening at opposite ends respectively at the front and rear faces of the block

structure; a plurality of picker spindles journaled in the block structure, one in each bore and normally constrained against axial separation from said structure, each spindle having a rear end including a driven element rearwardly engageable with and forwardly disengageable from a respective driving element; and releasable means securing the block structure to the column.

9. A picker bar, comprising: an elongated column of U-shaped section and having top and bottom open ends; the bight portion of the U affording an upright rear wall and the legs of the U respectively affording upright, forwardly projecting side walls, each side wall having an upright front edge and substantially horizontal top and bottom edges; top and bottom closure members secured respectively along said top and bottom edges and respectively having free front edges cooperative with the side wall front edges to define an elongated front opening in the column; an upright drive shaft journaled in the column and contained substantially coaxially in the bight portion thereof, said shaft having thereon axially spaced apart driving elements; elongated upright block structure rearwardly receivable in and normally supported by the column and forwardly removable from the column via the front opening for disassembly, said structure having a rear face proximate to but spaced forwardly from the drive shaft when received in the column and further having a front face exposed at the front of the column, said structure having therein a plurality of substantially horizontal spindle bores equal in number to and vertically spaced apart on the order of the driving elements on the shaft, each bore opening at opposite ends respectively at the front and rear faces of the block structure; a plurality of picker spindles journaled in the block structure, one in each bore and normally constrained against axial separation from said structure, each spindle having a rear end including a driven element rearwardly engageable with and forwardly disengageable from a respective driving element; and releasable means securing the block structure to the column.

10. The invention defined in claim 8; in which: the drive shaft is journaled in the column by means of coaxial circular bearings supported by the column independently of the block structure; and the cross-sectional shape of the bight portion of the column is less than

5 a full circle so as to enable engagement and disengagement between the driving and driven elements but is greater than a semicircle so as to embrace and support the bearings.

11. The invention defined in claim 8, in which: the drive shaft is supported in the column by means of a circular bearing supported in part by the column, the cross-sectional shape of the bight portion of the column being arcuate and in radial register with the bearing and engaging a portion of the bearing; and the rear face of the block structure has an arcuate portion in radial register with the bearing and engaging a portion of the bearing substantially diametrically opposite the bearing portion engaged by the bight portion of the column.

12. The invention defined in claim 11, in which: engagement of the arcuate portion of the block structure with the bearing determines proper engagement between the respective driving and driven elements.

13. A picker bar, comprising: an upright hollow support having a front side formed with a continuous upright opening; driving mechanism interiorly of the support and exposed through said opening; upright spindle-mounting means closing the opening comprising a plurality of separate spindle-mounting elements arranged 20 in vertically stacked relationship, each element having upper and lower guide surfaces, and each element except the lowermost element having its lower surface resting on the upper surface of the next lower element to be carried by said next lower element for movement selectively toward and away from the driving mechanism, said elements having a plurality of vertically spaced, substantially horizontal bores therethrough leading to the interior of the support; a plurality of picker spindles carried by and normally constrained to remain with the 25 elements, one spindle in each bore and each spindle having a driveable inner end separately associated with and driven by the driving mechanism; and means individually and removably securing each of the elements to the support.
